United States Patent Office.

GEORGE KELLOGG OSBORN, OF NEW YORK, N. Y.

Letters Patent No. 104,635, dated June 21, 1870.

IMPROVEMENT IN ARGAND OIL-BURNERS.

The Schedule referred to in these Letters Patent and making part of the same.

I, GEORGE KELLOGG OSBORN, in the city, county, and State of New York, have invented a certain Improvement in Burners, of which the following is a specification.

The object of my invention is to enable oil to be used for illumination in the ordinary gas-fixtures in place of gas.

The first part of my invention relates to the construction, combination, and use of a peculiar tube and pin.

The second part of my invention relates to a stop-cock, which acts the part of a ratchet for the wick, and as a stop-cock at the same time.

The third part relates to the general construction and arrangement.

Description of the Accompanying Drawing.

Figure 1 is a view of my burner, complete.

Figure 2 shows fig. 1, with the front half removed.

Figure 3 is a sectional view of fig. 1, at right angles with the view in fig. 2.

Figure 4 is a nearly vertical view of the lower section of fig. 1, bisected on a line, *x x*.

Figure 5 shows the float separated from the rest of the burner.

Figure 6 shows a view of the stop-cock and ratchet movement separate from the burner and in the same position as it occupies in fig. 1, and in its sectional view, fig. 2.

Figure 7 is a right-hand view of fig. 6.

Figure 8 is the spring, taken out of the burner.

Figure 9 is the tube complete and out of the burner.

Figure 10 is a sectional view of fig. 9.

Figure 11 shows the pin separate from the burner.

General Description.

C is a chamber surrounding the wick-tube U, and contains the float F.

W is a wick held between the wick-tubes U U.

I is a cap which incloses the pin-tube T and pin P.

It divides and passes on both sides of the center piece H, and connects with the stop-cock S, and forms a passage for the oil from the stop-cock to the orifice N, figs. 9 and 10, in the top of the pin-tube T.

The pin-tube is made in the form of a hollow cylinder with conical heads, with holes in the centers just large enough to admit of the passage of the pin P.

The hole N is for the entrance of the oil to the tube, and the one at the other end is a guide for the pin.

There is a hole, M, on the side of the tube T, for the exit of oil.

The pin P is like any ordinary pin, only having a suitable eye instead of a head, and is large enough to

reach the length of the pin-tube T, and fill both holes in the ends at once.

K is a straight wire spring, which passes through the eye of the pin P, and connects at both ends with the float F, and its use is to prevent injury to the pin by any hard jars given to the burner, and to connect the pin with the float.

L is a ring, to which the wick W is attached, and is moved up and down by means of the reach R, which connects with the arms A, which project from the stop-cock S, and is moved up and down by turning the stop-cock on or off.

The float F is a hollow ring, and light enough to float readily in oil, and touch nothing when in use but oil and the spring K.

The operation is as follows, viz:

The oil enters the burner at the point D, passes in the direction indicated by the arrows to the hole N, in the top of the pin-tube T. It enters the hole N, and, passing down the tube T, is discharged through the hole M into the center piece H H, through which it flows into the chamber C, and, passing through small holes at the bottom of wick-tube U, it enters the wick which conveys it to the top of the burner, where it is ignited.

If the oil flows into the chamber C faster than it is consumed, the chamber becomes half filled with oil, which raises the float which raises the spring K, and the spring K raises the pin until it enters the hole N at the upper end of the pin-tube T, which lessens the flow of oil until it equals the amount being consumed.

If the flame is increased it lessens the oil in the chamber C, the float falls, which lowers the pin enough to give room for a flow equal to the demand.

I am aware that there have been in use automatic gas-burners and automatic-regulating apparatus attached to lamps, but I am not aware of any oil-burner which regulates the flow of oil through itself automatically, as herein described.

What I claim, and desire to secure by Letters Patent, is—

1. The pin P and the tube T, when worked together and constructed substantially as and for the purpose herein set forth and described.

2. A stop-cock, which, as a ratchet, moves the wick and acts as a stop-cock at the same time.

3. The combination of the circular float F, spring K, and pin P, with the pin-tube T, cap I, wick-tubes U U, and oil-chamber C, when all are arranged to operate as herein described and shown.
